PAIR OF SPECTACLES

Stanley Switkes, Elmont, N.Y., assignor to Renaud International, Ltd., Fitchburg, Mass.

Filed Dec. 6, 1972, Ser. No. 312,544

Term of patent 14 years

Int. Cl. D16—06

U.S. Cl. D57—1 F

FIG. 1

FIG. 2

FIG. 3

FIG. 4

FIG. 1 is a front elevational view of a pair of spectacles showing my new design;

FIG. 2 is a top plan view thereof;

FIG. 3 is a side elevational view thereof; and

FIG. 4 is a rear elevational view thereof on an enlarged scale, the spectacles being fragmentarily shown for convenience of illustration.

The side not shown has substantially the same appearance at the side shown.

I claim:

The ornamental design for a pair of spectacles, substantially as shown and described.
